DESIGN FOR A WALL CLOCK

Frederick Lux, Waterbury, Conn., assignor to
The Lux Clock Manufacturing Company,
Waterbury, Conn., a corporation of Connecticut

Application March 16, 1940, Serial No. 90,978

Term of patent 7 years

To all whom it may concern:

Be it known that I, Frederick Lux, a citizen of the United States, residing in the city of Waterbury, in the county of New Haven and State of Connecticut, have invented a new, original, and ornamental Design for Wall Clocks, of which the following is a specification, reference being had to the accompanying drawing, forming part thereof.

Fig. 1 is a front view of the wall clock, showing my new design.

Fig. 2 is a side view of the same.

I claim:

The ornamental design for a wall clock, as shown.

FREDERICK LUX.
